UNITED STATES PATENT OFFICE.

CARL C. HINKLEY, OF DETROIT, MICHIGAN, ASSIGNOR TO CHALMERS MOTOR COMPANY, OF DETROIT, MICHIGAN, A CORPORATION OF MICHIGAN.

RADIATOR-FILLER-CAP MONOGRAM-LAMP.

1,201,732.

Specification of Letters Patent.

Patented Oct. 17, 1916.

Application filed December 31, 1915. Serial No. 69,519.

To all whom it may concern:

Be it known that I, CARL C. HINKLEY, a citizen of the United States of America, residing at Detroit, in the county of Wayne and State of Michigan, have invented certain new and useful Improvements in Radiator-Filler-Cap Monogram-Lamps, of which the following is a specification, reference being had therein to the accompanying drawings.

In the present state of the art in automobile construction it is quite usual to provide the radiator filler cap with monogram plates indicating the make of the car. These plates are conspicuously in view during daylight but at night cannot be seen as they are out of the range of illumination from the lamps.

It is the object of the present invention to provide a monogram cap which is equally discernible in the daylight or at night, and to this end the invention comprises the peculiar construction and combination of cap and lamp as hereinafter set forth.

In the drawings: Figure 1 is a front elevation; Fig. 2 is a section through the cap and lamp; and Fig. 3 is a diagrammatic plan view showing the location of the cap and the manner of connecting the electric circuits thereto.

30 A indicates the radiator of an automobile and B the filler cap therefor which as shown is in the form of a screw-cap. Mounted upon this cap B is a housing C for containing an electric lamp D and displaying at 35 the front the monogram face E. The housing may be formed of any suitable material, being preferably of an oval cross-section, and having at its back the concave reflector F. There is also provided a hollow base G, 40 which is secured to the cap by a bolt H, which bolt is extended within the hollow base to form the grounded terminal of the lamp.

I is the lamp socket secured within the 45 hollow base by a set-screw J. To insulate this socket from the terminal bolt H and also to prevent grounding on the radiator cap, the latter is provided with an insulator top K on which the hollow base G

rests. This hollow base is insulated from 50 the terminal bolt H by an insulator washer L.

M is a socket on the base G for receiving a plug or contact N secured to a flexible conductor O. The conductor O is preferably led to the cap between the outer frame and 55 core of the radiator so as to be concealed with the exception of a small portion passing through an aperture P in the outer frame and extending to the socket M.

The monogram or other device exhibited 60 on the lamp may be made in any suitable way to be visible either by reflected or transmitted light. As shown the glass front is formed of two parallelly-arranged glasses E and E', the inner one being preferably 65 a white translucent material and the outer one having a colored surface with the monogram or design etched therein. This will render the design visible in daylight, while at night when the lamp is in circuit the design will appear as a transparency.

The construction as described is one which does not in any way interfere with the normal function of the radiator cap, as the latter may be detached when necessary by 75 first disengaging the plug N from the socket M, after which the cap may be unscrewed.

It is obvious that if desired in place of having one terminal of the lamp grounded a complete insulated circuit may be used. 80

What I claim as my invention is:

1. The combination with a radiator cap, of an insulator cover therefor, a housing mounted on said cover, an electric lamp within said housing, a terminal for said lamp insulated from said housing and grounded on said cap, and a terminal connected to said housing. 85

2. The combination with a radiator, of a cap therefor, an electric lamp mounted on said cap, a conductor for current to said lamp partially extending between the outer frame and core of the radiator, and a flexible extension to said conductor passing out from said frame adjacent to said cap and detachably connected thereto. 90

3. The combination with a radiator cap, of a housing mounted on said cap, insulat-

ing material between said cap and housing, an electric lamp within said housing, and electric connections to said lamp permitting of the removal of said radiator cap.

5. 4. The combination with a radiator cap, of an insulator cover therefor, a housing mounted on said cover provided with a hollow base, a bolt for securing said hollow base to the cap insulated from said base

and grounded on said cap, an electric lamp 10 within said housing, and a terminal connected to said base.

In testimony whereof I affix my signature in presence of two witnesses.

CARL C. HINKLEY.
